UNITED STATES PATENT OFFICE.

CLARENCE H. WALTHALL, OF MONTGOMERY, WEST VIRGINIA, ASSIGNOR OF TWO-FIFTHS TO ROBERT A. WITHROW, OF MONTGOMERY, WEST VIRGINIA.

MEANS FOR TRANSPORTATION OF ROLLING STOCK.

Application filed April 19, 1926. Serial No. 102,942.

My present invention relates to improved means for the transportation of railway rolling stock as freight.

The principal object of my invention is the provision of means adapted to be used in connection with a freight car, whereby rolling stock may be nested or packed thereon and held securely in such car without movement which would otherwise damage the parts of said rolling stock.

Another object of this invention is the provision of means as above which is adjustable to secure various members of such devices quickly and without complicated parts, which may be readily attached to a flat or gondola car of the freight type, which may be made from waste or other material, and which therefore will be of maximum efficiency.

To this end my invention consists in the provision of a track or tracks secured to the bed of a flat or gondola freight car, which track may consist of rails or other suitable material, but which will be referred to herein as rails. The spacing of such rails will depend upon the gauge of the rolling stock to be transported.

Secured to such rails in an adjustable manner, and at each end thereof, I provide retaining members adapted to engage the rolling stock resting upon said rails, in such manner that they cannot be accidentally displaced thereon.

The invention further consists in the novel combination, construction and arrangement of parts hereinafter described and shown in the accompanying drawings.

In these drawings, which illustrate one embodiment of my invention:

Figure 1 is a plan view of a freight car bed equipped with my device.

Fig. 2 is a side elevation of Fig. 1.

Fig. 3 is a side elevation of the adjustable retaining member.

Fig. 4 is a transverse sectional view along the line 4—4 of Fig. 3.

Referring particularly to the embodiment illustrated, I have represented at 1 a freight car bed, which car may be either of the flat or gondola type although the flat car type is preferable.

To the bed 1 I spike or otherwise secure, a pair of rails 2 and a second pair 3. The distance of separation of the individual rails

of each pair will depend upon the gauge of rolling stock to be shipped. I may very advantageously make use of old or worn out rails for this purpose, although this is not essential. Likewise such rails may be made of wood or the like.

It is to be noted that each pair of rails straddle a rail of the other pair. This is desirable in order that the rolling stock may be nested or staggered upon the car, that is, the wheels of one assembly will contact with or lie adjacent to the axle and journal of its neighbor. In this manner the maximum number of rolling stock assemblies may be accommodated.

Located between corresponding individual rails of the pairs 2 and 3 I provide a retaining assembly comprising a bent rail having a horizontal portion 4 and an upstanding part 5 to which rail is secured in any desired manner the spacing pieces 6 and 7. In the form shown such spacing pieces comprise pressed metal frames riveted to rail part 4 and lying between the head and flange of one of the rolling stock supporting rails and adjacent the web thereof. The outer edges of spacing pieces 6 and 7 are beveled as at 8 and 9 to accommodate the flange on the wheels of the rolling stock. This bevel is particularly necessary where old or worn out rails are utilized to comprise the pairs 2 and 3, as in such instances the head is often partially or most completely worn down.

It is desirable that the combined width of spacing pieces 6 and 7, and rail pair 4 be just slightly less than the distance between webs of the corresponding individual rails of pairs 2 and 3 in order that the retaining assembly may be readily adjusted between them.

Corresponding apertures are provided in rail pairs 2 and 3, and the retaining assemblies as at 10 through which pins 11 may be slipped in order to secure the retaining assemblies in their desired position. The pins 11 may be locked in place by means of nuts 12, or in any other desired manner.

It is to be understood that similar pairs of retaining assemblies are to be provided at each end of the car bed.

The rolling stock having been loaded upon the pairs of rails 2 and 3, the retaining assemblies may be adjusted toward each other

by proper manipulation of the pins 11 so that the rolling stock will be securely held against accidental displacement during shipment. It will be noted that when the parts have been properly adjusted relative to the rolling stock, one upturned rail part 5 will engage the axle of the outside stock, the other corresponding rail part engaging the journal projecting beyond the wheel of the same stock. In like manner the pair of retaining assemblies at the other end of the car will similarly engage and hold securely the wheel axle assembly at that end. Thus a plurality of units of rolling stock may be staggered upon a car bed, each touching its neighbor, the end stock being held against accidental displacement, and therefore the entire number may be safely transported.

Obviously other than rails may be used as the bent members 4 and 5, as this may take the form of a bar, having its end bent upwardly so as to engage an axle or journal of the stock.

Having thus described my invention, what I claim is:

1. In combination, a car bed, a pair of supporting rails thereon, rolling stock retaining means secured to said rails, said means adapted to engage said stock at its axle and journal portions.
2. In combination, a car bed, two pairs of supporting rails thereon in straddling relation, and rolling stock retaining means se-

cured between corresponding rails of said pairs.

3. In combination, a car bed, two pairs of supporting rails thereon in straddling relation, and rolling stock retaining means secured between corresponding rails of said pairs, said means including an upwardly projecting element adapted to engage rolling stock upon said rails.

4. In combination, a car bed, two pairs of supporting rails thereon in straddling relation, and rolling stock retaining means secured between corresponding rails of said pairs, said means including a bent rail secured to spacing pieces on each side thereof.

5. In combination, a car bed, two pairs of supporting rails thereon in straddling relation, and rolling stock retaining means secured between corresponding rails of said pairs, said means including a bent rail secured to spacing pieces on each side thereof, said spacing pieces engaging the corresponding rails of each pair adjacent their webs.

6. In combination, a car bed, two pairs of supporting rails thereon in straddling relation, and rolling stock retaining means secured between corresponding rails of said pairs, said means including a bent rail secured to spacing pieces on each side thereof, said spacing pieces being beveled at their outer edges.

In testimony whereof, I affix my signature.

CLARENCE H. WALTHALL.
